Primary Examiner — Samantha Q Lawrence*(74) Attorney, Agent, or Firm* — Muetting Raasch Group(57) CLAIM

We claim the ornamental design for a sex toy, as shown and described.

DESCRIPTION

FIG. 1 is a front view of a sex toy;

FIG. 2 is a back view thereof;

FIG. 3 is a perspective view thereof;

FIG. 4 is a side view thereof;

FIG. 5 is a top view thereof; and,

FIG. 6 is a bottom view thereof.

The broken lines shown in FIG. 6 illustrate portions of the sex toy and form no part of the claimed design.
